DESIGN FOR A PLIER TYPE STAPLING
MACHINE

John Fancher, Chatham, N. J., and Lou Obstfeld, Brooklyn, N. Y.; said Fancher assignor to Abraham Obstfeld, New York, N. Y.

Application February 7, 1939, Serial No. 82,826

Term of patent 14 years

To all whom it may concern:

Be it known that we, John Fancher and Lou Obstfeld, citizens of the United States and residents, respectively, of Chatham, in the county of Morris and State of New Jersey, and Brooklyn, in the county of Kings and State of New York, have invented a new, original, and ornamental Design for a Plier Type Stapling Machine, of which the following is a specification, reference being had to the accompanying drawing, forming a part thereof, wherein:

Fig. 1 is a front elevation of a plier type stapling machine embodying our design;

Fig. 2 is a plan view of the same;

Fig. 3 is a bottom view of the same;

Fig. 4 is an end elevation looking at the right-hand end of Fig. 1; and

Fig. 5 is an end elevation looking at the left-hand end of Fig. 1.

The dominant features of the design are shown in full lines.

We claim:

The ornamental design for a plier type stapling machine, substantially as shown and described.

JOHN FANCHER.
LOU OBSTFELD.
